UNITED STATES PATENT OFFICE.

ROY H. BROWNLEE, OF PITTSBURGH, PENNSYLVANIA.

TUBING CONSTRUCTION.

1,329,285.

Specification of Letters Patent. Patented Jan. 27, 1920.

Application filed September 22, 1919. Serial No. 325,436.

To all whom it may concern:

Be it known that I, ROY H. BROWNLEE, a citizen of the United States, and resident of Pittsburgh, in the county of Allegheny and 5 State of Pennsylvania, have invented a new and useful Improvement in Tubing Constructions, of which the following is a specification.

This invention relates to a tubing construction for use in tubular oil stills, water tube boilers, and for any other purpose of 10 the same general nature in which a metallic tubular structure contains vaporizable matter and is subjected to relatively high temperatures and pressures.

One object of the invention is to provide 15 a metallic tubing construction so arranged that access to all lengths of the tubing employed in an installation may be had from the exterior of the furnace, and a cleaning tool readily run through each length of tubing. Another object of the invention is to provide a tubing structure which furnishes a continuous and jointless path for the hot 20 vapors therein, and in which the joints are located exteriorly of the furnace so that they are readily accessible and are not subjected to high temperature and hot vapors. A further object of the invention is to provide a 25 construction in which the tubes employed are so cut, matched, and welded that an integral structure with smooth and firm connections is provided.

In the accompanying drawings, Figure 1 30 is a diagrammatic vertical section through a furnace showing a tubing system embodying the construction of the present invention in position therein; Fig. 2 is a diagrammatic rear elevation of the furnace; Fig. 3 is an 35 elevation of a connection between two adjacent heating tubes and their connecting tube; Fig. 4 is an end view of the connecting tube showing the heating tubes joined thereto; Fig. 5 is a section through the 40 connecting tube on the line 5—5 Fig. 3; Fig. 6 is an elevation of that portion of one of the 45 heating tubes which is adjacent the point of connection; Fig. 7 is a view similar to that of Fig. 3 but illustrating a modified cutting 50 of the tubes; Fig. 8 is an end view of the connecting tube and heating tubes of the modified construction; Fig. 9 is an elevation 55 of one of the heating tubes of this construction, and Fig. 10 is a cross section on the line 10—10 Fig. 7.

In the drawings, 1 is a continuous tubing

structure set in a furnace 2, and arranged to extend vertically a considerable proportion of the height of the furnace. This tubular structure or tubing system 1 comprises a plurality of relatively long sections 3, which are arranged to be exposed to heat in the furnace, and which are inclined to the vertical and joined to form a continuous circuitous length of tubing; and shorter sections 4 of greater diameter than the sections 3 and to which the latter are welded. The ends of adjacent tubes 3 are connected with each other and with the exterior of the furnace by means of their mutual connecting tube or section 4. Each section 4 is arranged to extend beyond the outer face of the furnace wall and is closed at its outer extremity by means of a packing flange 5, which may be of any usual form.

In order to form a smooth joint with the heating tubes 3 which connect with it, and to permit a cleaning tool to be more readily passed through it and into either of the heating tubes, the connecting tube 4 is made of a slightly greater diameter than the heating tubes. At its inner extremity, as shown in Figs. 3 and 5, the tube 4 is flattened out from a tube of circular cross section into one of a generally elliptical section of such dimensions that its shorter axis is equal to the diameter of the heating tubes 3.

The inner end of the tube 4 is also cut away in two angular directions from approximately its median line to form two equal edges or faces 6, as is shown in Figs. 3 and 5. Each of the tubes 3 to be joined thereto is preferably bent so as to provide a portion 7 curving toward the connecting tube. This is in order that the tubes 3 may be more rapidly matched with the end of the connecting tube 4, and also in order that vapors passing through the tubes will not be directed into and along the connecting tube. At the extremity of such curved portions, each of the tubes is cut away as at 8, in Figs. 3 and 6, to match the cut edges 6 of the connecting tube. It will be seen that the angle at which the ends of the tubes 3 must be cut will depend upon the degree of curvature of the portions 7, the angle at which they approach the tube 4, and the angle at which the tube 4 is cut. When so desired, certain of the adjacent heating tubes may be arranged parallel to each other and their adjustment to the end of their connecting tubes made by the curvature of their end

portions and the angle at which they and the connecting tubes are cut.

In making the tube construction, the heating tubes and the connecting tube are cut 5 into the forms above described by any convenient means. Preferably, such cutting is performed by means of a welding and cutting torch using a suitable cutting gas. The tubes are then brought together into the 10 position shown in Fig. 3, and the joints are welded by the use of the welding torch and a thin welding rod. In the welding operation, this welding rod is passed along the lines of division between the tube sections 15 while the flame of the torch is being applied thereto, so that such lines of division are covered with a smooth coating of metal from the rod and a firm and smooth welded connection made.

20 In the form of the construction having a modified matching of the tubes, as illustrated in Figs. 7 to 10 of the drawings, the inner portion of the connecting tube 4 is flattened, as in the previously described 25 form, into an elliptical section the shorter axis of which is equal to the diameter of the heating tubes 3. The end or edge of the tube is, however, normal to the longitudinal axis of the tube instead of being cut away 30 on planes at an angle thereto. Both legs of heating tubing 3 are, in this form also, bent to form curved portions 7 adjacent their extremities. Instead however, of being cut in one direction, as in the other form, it is 35 necessary that they be cut twice in order that they may match with each other and with the connecting tube. They are, therefore, cut along the lines 9 and 10, both cuts being at an angle to the longitudinal axis of the 40 tube and meeting at the point 11.

In matching the tubes for welding, the edges 10 of the tubes 3 are brought into contact with each other and the edges 9 are brought into contact with the edge of the 45 tube 4, as is shown in Fig. 7.

In making the weld, the process is in general similar to that previously described. It will be noted, however, that the line 10, along which the tubes 3 are cut and along 50 which they are in contact with each other, is not, even at its deepest point, equal to the diameter of the tubes. It is necessary, therefore, that metal be supplied from the welding rod to bridge over the space thus left 55 open in the face of the tube 4. This filled space is indicated at 12 in Figs. 8 and 10 of the drawings. The connection thus formed, while not so smooth as that formed in the manner illustrated in Figs. 3 to 6 inclusive, 60 is yet relatively so, and is strong and serviceable.

The construction above described provides a neat and strong welded connection between two lengths of tubing set at an angle to each 65 other, and a third tubular section set at such

an angle thereto as to furnish access to the interior of both lengths of tubing.

It will be readily seen that the tubing structure may be built up of any desired number of lengths of heating tubing and a 70 proportional number of connecting sections, thus furnishing a continuous, jointless, and circuitous tube of any desired length. The structure when installed in a furnace reduces possible leakage to a minimum, since 75 the path of the vapors through the tubing is such that a large volume of hot vapors cannot come directly into contact with the packing flange 5. This feature is of particular importance when the construction is used 80 to form a tubular oil still, as oil vapors, when heated to a high temperature, are destructive to packing and are particularly liable to leak through joints against which a stream of such vapors impinges directly. 85 The flange 5 is protected from the heat of the furnace, and from the heated vapors by the length of the tube 4, this length being as great as is advantageous in the particular use for which the construction is installed. The flange is also protected from the hot vapors by the fact that the curved portions 7 of the heating tubes so direct the stream of vapors that only a small proportion of such stream penetrates any appreciable distance into the tube 4.

To clean the heating tubes, the flanges 5 are removed, and a suitable cleaning tool, such as an air operated tube cleaner, passed through the connecting tubes 4 into the tube 100 3. This cleaner with its flexible connection may be inserted into either of the heating tubes to which each tube 4 is welded and can be easily passed through the tube. Each tube may also be cleaned from either end, 105 or from both ends successively. This accessibility for cleaning is also of particular importance where the construction is used as a tubular oil still, as it permits frequent removal of carbon from the tubes without requiring the furnace to be cooled prior to the 110 cleaning operation.

As a number of modifications may be made in the device without departing from the spirit of the invention, no limitations 115 other than those contained in the appended claims are to be imposed. One such modification would consist in so arranging the series of tubes that they would form a continuous circuitous pipe extending horizontally of the furnace instead of one extending vertically as shown.

What I claim is:

1. A tubing construction for a fire-heated furnace comprising a plurality of metallic 125 heating tubes, adjacent tubes being set at an angle to each other; and metallic connecting tubes of greater diameter than the heating tubes arranged to project beyond the furnace wall and to the inner end of each 130

of which the adjacent heating tubes are so welded that access may be had to the interior of both of said adjacent heating tubes from the exterior of the furnace through 5 said connecting tube.

2. In a tubing construction a furnace, a tube extending through the wall of said furnace, and a pair of heating tubes disposed at an angle to said horizontally disposed tube and welded to the inner extremity thereof.

3. In a tubing construction a furnace, a tube extending substantially horizontally through said furnace wall, and a pair of 15 heating tubes disposed at an angle of less than forty-five degrees to said horizontally disposed tube and welded thereto.

4. A metallic tubing construction comprising a connecting tube of regular cross 20 section, and a pair of heating tubes set at an angle to each other and cut away at their extremities on planes at an angle to the longitudinal axis of the tubes and welded to one end of said connecting tube.

25 5. A metallic tubing construction comprising a connecting tube, and a pair of heating tubes curved toward each other adjacent their connected extremities and having such extremities cut away on planes at an 30 angle to the longitudinal axis of the tubes and welded to one end of said connecting tube; said connecting tube being of greater diameter than the heating tubes and flattened adjacent its connecting extremity to 35 a regular cross section having its shorter axis equal to the diameter of the heating tubes.

6. A metallic tubing construction comprising a connecting tube of regular cross section, and a pair of heating tubes curved toward each other adjacent their extremities and having their extremities cut away on planes at an angle to the longitudinal axis 40 of the tubes and welded to one end of said connecting tube.

45 7. A metallic tubing construction comprising a connecting tube, and a pair of heating tubes having their extremities cut away on planes at an angle to the longitudinal axis

of the tubes and welded to one end of said 50 connecting tube; said connecting tube being of greater diameter than the heating tubes and flattened adjacent its connecting extremity to a regular cross section having its shorter axis equal to the diameter of the 55 heating tubes.

8. A welded tubing construction comprising a pair of heating tubes set at an angle to each other, and a connecting tube of greater diameter than said heating tubes 60 and flattened adjacent one extremity to a regular cross section having its shorter axis equal to the diameter of the heating tubes; said heating tubes being each cut away adjacent their connecting extremities on two 65 planes at an angle to the longitudinal axis of the tubes to match with and be welded to each other and the flattened end of the connecting tube.

9. A metallic tubing construction comprising 70 a connecting tube of regular cross section, and a pair of heating tubes set at an angle to each other and curved toward each other adjacent their extremities; said heating tubes having their extremities cut away 75 on planes at an angle to the longitudinal axis of the tubes and welded to one end of said connecting tube.

10. A welded tubing construction comprising 80 a pair of heating tubes set at an angle to each other and curved toward each other adjacent their extremities, and a connecting tube of greater diameter than said heating tube and flattened adjacent its extremity to a regular cross section having its shorter 85 axis equal to the diameter of the heating tubes; said heating tubes being each cut away adjacent their connecting extremities on two planes at an angle to the longitudinal axis of the tubes to match with and be 90 welded to each other and the flattened end of the connecting tube.

In testimony whereof I hereunto set my hand.

ROY H. BROWNLEE.
